[57] CLAIM

The ornamental design of an octagon shaped lighting fixture, as shown as described.

DESCRIPTION

FIG. 1 is a perspective view of a first embodiment of the

lighting fixture of my invention without the reflector system shown;

FIG. 2 is a top view of the lighting fixture in FIG. 1;

FIG. 3 is a front perspective view of the lighting fixture in FIG. 1, the rear view being identical to the front view;

FIG. 4 is a right side perspective view of the lighting fixture in FIG. 1, the left side view being identical to the right side view;

FIG. 5 is a bottom view of the lighting fixture in FIG. 1 without the reflector system shown;

FIG. 6 is a perspective view of a second embodiment of the lighting fixture of my invention;

FIG. 7 is a top view of the lighting fixture in FIG. 6;

FIG. 8 is a front perspective view of the lighting fixture in FIG. 6, the rear view being identical to the front view;

FIG. 9 is a right side perspective view of the lighting fixture in FIG. 6, the left side view being identical to the right side view; and,

FIG. 10 is a bottom view of the lighting fixture in FIG. 6.
